CLAIM

The ornamental design for a combined housing and bus bar support panel for an electrical load center, as shown and described.

DESCRIPTION

FIG. 1 is a perspective view of a combined housing and bus bar support panel for an electrical load center showing our new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof;

FIG. 7 is a bottom plan view thereof; and

FIG. 8 is a perspective view of a combined housing and bus bar support panel for an electrical load center showing my new design with circuit breakers mounted on the bus bar panel. The broken line showing of the circuit breakers is included for the purpose of illustrating environmental elements only and forms no part of the claimed design.

FIG. 1

FIG-2-FIG-3-FIG-4-FIG-5-FIG-6-

FIG-7-

FIG-8-
